BRAIDER CARRIER

Robert V. Olson and Bror A. Johnson, Attleboro,
Mass., assignors to Mossberg Pressed Steel
Corporation, a corporation of Massachusetts

Application April 29, 1935, Serial No. 18,835

9 Claims. (Cl. 96—15)

This invention relates to a braider carrier, particularly a carrier which is designed to run under very heavy tension; and the invention has for one of its objects the provision of means for preventing the package or bobbin from unduly lifting away from the feed control latch and thereby preventing an excessive let-off of the yarn from the package.

Another object of the invention is the provision of means which acts as a stop limiting the upward movement of the bobbin or package and which can be readily disconnected and swung to such a position as to permit of a fresh supply package on the carrier.

Another object of the invention is to secure all of the upright posts together for a more rigid support for the thread eye at the top of the carrier.

Another object of the invention is to tie together the upright post and bobbin spindle for a more firm support of the post and the thread guide eye which is mounted or connected therewith.

Another object of the invention is to provide the thread guide bail with a connection at its top to the plurality of posts and to also cause this bail to tie in with the connection between the post and the spindle for making a rigid connection of the parts.

With these and other objects in view, the invention consists of certain novel features of construction, as will be more fully described, and particularly pointed out in the appended claims.

In the accompanying drawing:

Fig. 1 is an elevation of the braider carrier with the bobbin or package mounted thereon, and illustrating the yarn, in one position with relation to the parts;

Fig. 2 is a view at right angles to that shown in Figure 1 with the package removed;

Fig. 3 is a sectional view on line 3—3 of Figure 1;

Fig. 4 is a perspective view of the member which prevents the rise of the bobbin package;

Fig. 5 is a fragmental perspective view of the upright posts, the upper end of the bail and the upper end of the bobbin spindle;

Fig. 6 is a top plan view of a modified construction of the connection of the top of the posts and spindle;

Fig. 7 is a section on line 7—7 of Figure 6.

In the running of braider carriers where a very heavy tension is employed, it sometimes occurs that the bobbin package due to this high tension is caused to lift away from the latch which controls the feed of the yarn from the package and there is let off an excessive amount of yarn to the

detriment of the action of the carrier. Also, the strain due to such heavy tension is not as well supported at the end of long or high posts due to vibration which may occur in the carrier; and in order to avoid these undesirable effects, we have secured together the posts and also connected the posts and the spindle for the bobbin package and have so arranged the securing means that it will limit the upward movement of the yarn or bobbin package so that it cannot disengage the feed control latch; and the following is a more detailed description of the present embodiment of this invention, illustrating the preferred means by which these advantageous results may be accomplished:

With reference to the drawing, 10 designates the base of the carrier having quilt plate engaging surfaces 11 and 12 which are connected by a web 13 for travel in the raceway provided in the bed plate, the gear engaging stud being designated 14.

Extending upwardly from the base of the carrier there is provided a spindle 15 upon which the bobbin or yarn package 16 with its heads 17 and 18 is mounted. Head 18 is provided with a suitable ratchet formation 19 to be engaged by the latch 20 pivoted at 21 on the base and operated by the latch lift 22 which is guided by the post 23 and operated by the tension weight 24 slideable on the post 25, the usual spring 26 forces the latch lift 22 downwardly while the long acting spring 27 which encircles the post 25 engages the weight to force it downwardly in a known manner. Both the latch guide post 23 and the weight guide post 25 extend to a height substantially as high as the spindle 15.

The yarn 28 in being drawn from the package 16, passes through the thread guide eye 29 which is mounted on the latch lift post 23 thence beneath the thread guide portion 30 of the tension weight and thence through the pigtail guide 31 mounted on the upper end of the latch lift guide post 23. The upper end of the posts 23 and 25 are connected together by a link 33 which is slidably mounted on the post 23 and is held by a threaded nut 34 and check nut 35 in engagement with the link 33, as more clearly shown in Figure 5. This link, of course, is urged upwardly by a spring 27 on the tension weight post 25.

A thread guide bail 36 for equalizing the yarn angle is suitably secured in the base as at 37 and passes through the link 33 where it is threaded and held on either side of the link 33 by nut 38, 39 screwed into firm engagement therewith. In this manner, the two posts 23 and 25 are firmly secured together at their upper ends while the

thread guide bail 36 is also secured thereto, thus forming a rigid support for the upper thread guide 31.

A sleeve 40 closely slidably fits the post 25 above the tension spring and is provided with a member 41 extending upwardly as at 42 thence horizontally as at 43 and bent to form a clip as at 44 to resiliently detachably engage a groove 45 in the end of the spindle 46 so that this member 41 may be swung about the post 25 as a center to and from engagement with the spindle 46 while its horizontal portion 43 which extends over the top of the bobbin package will effectively prevent the package from rising on the spindle to an extent to become disengaged from the latch 20 and allow undue rotation of the let-off of the yarn.

The resilient portions or jaws 47 and 48 extend a little more than half-way around the circumference of the recess 49 so as to grip the same 20 against accidental swinging of the parts away from engaging position.

In Figures 6 and 7 we show a different or modified construction in which the link now designated 50 is provided with a bore 51 for pivotally mounting the member 41 and in this case the tension spring 27 contacts with the under surface of the link, although the link is prevented from movement by the nuts 38 and 39 on the bail. In this case, however, the changing of tension springs 27, 30 it is merely necessary to remove the nut 39 and disengage the member 41 when the link may be slid upwardly to permit removal of the spring and replacement of a spring of different tension. The stop or retaining member 43, however, will function as before even though the point of pivoting is slightly different in the modified form.

The foregoing description is directed solely towards the construction illustrated, but we desire it to be understood that we reserve the privilege 40 of resorting to all the mechanical changes to which the device is susceptible, the invention being defined and limited only by the terms of the appended claims.

We claim:

- 45 1. In a braider carrier, a package spindle, a plurality of posts spaced therefrom, means provided with an opening therein and connecting said posts together at their upper ends, a member having a portion positioned in said opening and movably secured to said means to swing in a horizontal plane and detachably connect said spindle to said posts adjacent its upper end to assist in the rigidity of said posts.
- 50 2. In a braider carrier, a package spindle, a post removed therefrom, and a wire member

swingably mounted on said post and provided with a doubled back portion forming a resilient clip detachably engageable with said spindle.

3. In a braider carrier, a package spindle, a post removed therefrom, a spring on said post, a sleeve swingably mounted on said post and seated on said spring, and a member mounted on said sleeve and detachably engaging said spindle.

4. In a braider carrier, a package spindle, a weight post substantially as high as the spindle, a spring on said weight post, a member mounted on said post above said spring and having a portion extending to said spindle and detachably engageable therewith.

5. In a braider carrier, a package spindle, a 15 weight post substantially as high as the spindle, a spring on said weight post, a member on said post above said spring with an end portion provided with an inherently resilient clip for detachable engagement with said spindle.

6. In a braider carrier having a base, a package spindle having a groove at its upper end and raising from the base, a post spaced from said spindle and raising from said base, and a member movably mounted on said post to swing in a 25 horizontal plane and provided with a portion detachably clasping said spindle in the grooved portion thereof to connect said spindle and said post to assist in the rigidity thereof.

7. In a braider carrier, a package spindle having a groove at its upper end, a post removed therefrom, and a member pivotally mounted on said post to swing in a horizontal plane and having a portion detachably engaging said spindle 30 in the grooved portion thereof to block the raise of the package on said spindle.

8. In a braider carrier, a package spindle, a post removed therefrom, a coil spring embracing said post, a sleeve resting on the upper end of said spring and movably embracing said post to 40 be rotatable thereabout, and a member secured to said sleeve to move therewith and detachably engage said spindle.

9. In a braider carrier, a tension weight post, a second post, a link having an opening therein 45 and connecting said posts at their upper end, a guide bail provided with an adjustable abutment adjacent the upper end thereof engaging said link, an extension on said bail above said abutment extending through said opening, and means engaging said extension and link for positively securing said bail at its upper end thereto.
